UNITED STATES PATENT OFFICE

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed July 19, 1928. Serial No. 293,956.

My invention relates to railway traffic controlling apparatus, and particularly to apparatus of the type involving train-carried governing mechanism controlled by train governing current in the track rails. More specifically the present invention relates to the trackway portion of such apparatus, and has for an object the provision of means for obtaining recurrent acknowledgment of successive stop signals by delaying the application of train governing current to the track rails when a train enters a section the signal for which indicates "stop".

I will describe two forms of apparatus embodying my invention, and will then point out the novel features thereof in claims.

In the accompanying drawing, Fig. 1 is a diagrammatic view showing one form of apparatus embodying my invention, and Fig. 2 is a view showing a modification of portions of the apparatus shown in Fig. 1 and also embodying my invention.

Referring first to Fig. 1, the reference characters 1 and 1^a designate the track rails of a railway track along which traffic normally moves in the direction indicated by the arrow. These rails are divided by insulated joints 2 into a plurality of sections of which only one complete section C—D is shown in the drawing.

The section C—D is provided with a track circuit comprising a battery 3 connected across the rails at the exit end of the section through a reactor 4, a resistance 5, and the secondary of a transformer A. A direct current track relay T^c is connected across the rails at the entrance end of the section, and this relay is, of course, responsive to track circuit current furnished by the battery 3.

An insulated joint 2^a is interposed in the rail 1^a at an intermediate point in the section C—D, and an auxiliary track relay F is connected with the rail 1^a on opposite sides of this joint. As here shown, a full-wave rectifier G is interposed between the track rail and the relay, the input terminals of this rectifier being connected with the rail on opposite sides of the joint 2^a and the output terminals of the rectifier being connected with the relay F.

Section C—D is provided with a signal S^c, which signal is controlled by a front contact 8 of a signal relay H^c through a circuit which is obvious from the drawing. It is understood that the reference characters B and O designate the terminals of a source of current which furnishes the energy for the operation of the signal. Relay H^c is provided with a circuit which passes from terminal B, through a contact E^c, front contact 6 of relay F, front contact 7 of relay T^c, and the winding of relay H^c to terminal O. Contact E^c is operated by a manually operable lever in an interlocking machine which will usually be located in a tower adjacent the section C—D. Contact E^c is normally open, so that signal S^c normally indicates "stop", but when contact E^c is closed signal S^c will give a "proceed" indication if and only if both of the track relays T^c and F are energized. Signal S^c will also usually be controlled by traffic conditions in advance of section C—D, but the apparatus for accomplishing this control is omitted from the drawing, because it forms no part of my present invention.

It will be seen from the foregoing that track relays T^c and F are both normally energized by current from battery 3, but that when a train enters section C—D it immediately de-energizes relay T^c, and it later de-energizes relay F when the front axle of the train passes insulated joint 2^a.

The purpose of the transformer A is to supply alternating train governing current to the rails of section C—D, and this current is periodically interrupted at one frequency or another by means of a coding device Z^p. This device comprises two contacts 19 and 20, which are periodically closed at different rates while the device is energized. The coding device Z^p is controlled by a coder relay K^p in such manner that when the relay is de-energized the coding device is likewise deenergized and so is at rest. When the coder relay K^p is energized, the coding device Z^p is also energized by virtue of a circuit which passes from terminal X of a source of alternating current through front contact 18 of relay K^p and the winding of coding device Z^p to terminal Y of the same source of current. When

the coder relay K^D is energized, alternating current is supplied to the primary of transformer A, through contact 19 or 20 according as signal relay H^D for the section next in advance of point D is de-energized or energized. Assuming that relay H^D is energized, the circuit for the primary of transformer A is from terminal X, through contact 18 of coder relay K^D , contact 20 of the 10 coding device Z^D , front contact 21-21^a of relay H^D and the primary of transformer A to terminal Y. If relay H^D is de-energized, the circuit is the same except that it includes contact 19 of the coding device Z^D and back contact 21-21^b of relay H^D .

Coder relay K^D is provided with a pick-up circuit which passes from terminal B, through back contact 9 of track relay T^C , wire 10, contact N^C , wires 11 and 12, and the 20 winding of relay K^D to terminal O. Contact N^C is operated by signal S^C , and is closed when this signal gives a proceed indication, but is open when this signal indicates stop. This pick-up circuit is provided with a branch 25 around contact N^C , which branch includes back contact 16 of the auxiliary track relay F and wire 17. Relay K^D is provided with a stick circuit which passes from terminal B through back contact 9 of relay T^C , wire 13, front contact 14 of relay K^D , wire 15 and the 30 winding of relay K^D to terminal O. It follows from the forgoing, that when a train enters section C—D, relay K^D immediately becomes energized if signal S^C indicates proceed, but that if signal S^C indicates stop the 35 energization of relay K^D is delayed until relay F becomes de-energized. When relay K^D does become energized, it remains energized by virtue of its stick circuit as long as track 40 relay T^C remains de-energized.

The apparatus shown in Fig. 1 is suitable for cooperation with train-carried governing means requiring the supply of periodically interrupted alternating current to the track 45 rails to prevent a stop indication of any suitable kind, such as an automatic application of the brakes. If the supply train governing current is discontinued, a stop indication will result unless the engineman takes proper 50 action to acknowledge the change in traffic conditions. If he does acknowledge, the train may proceed without incurring a stop indication, but if train governing current is again supplied to the rails and this current 55 is subsequently discontinued, the engineman must again acknowledge to prevent a stop indication. One form of train-carried governing means operating in this manner and suitable for co-operation with the trackway 60 apparatus herein disclosed, is shown and described in application for Letters Patent of the United States filed by Lloyd V. Lewis on August 2, 1927, Serial No. 210,165, for Railway traffic controlling apparatus.

65 The operation of the apparatus shown in

Fig. 1 is as follows: Assuming first that signal S^C is in one of its proceed positions when a train enters section C—D, the coder relay K^D will be set into operation at once, and so the train will be supplied with alternating train governing current periodically interrupted at one frequency or the other, depending on traffic conditions in advance of this section. This coded current passes freely 70 around joint 2^a through rectifier G and relay F, and so reaches the train while the train is between point C and joint 2^a. If, however, signal S^C indicates stop when the train enters section C—D, the supply of train governing current will be delayed until the front 75 axle of the train reaches insulated joint 2^a, and so a stop indication will be given abroad the train unless the engineer takes suitable action to acknowledge the stop indication of signal S^C . This operation will be repeated 80 at each successive signal if the signal indicates stop.

The distance between point C and the insulated joint 2^a should be at least sufficient to insure that the highest speed train will consume enough time in traveling this distance to de-energize the de-coding relay which forms part of the locomotive equipment. In actual practice the minimum for this distance will probably be about 300 feet. It should be understood, however, that the distance between 90 C and 2^a might be made the entire length of the track section less a short distance of approximately 300 feet, in which case the train would receive no train governing energy 95 throughout the greater portion of the track section, and the distance between the insulated joint and point D would constitute a short re-set section to guarantee recurrent acknowledgment of signal S^D if the latter signal 100 should be in the stop position.

Referring now to Fig. 2, I have in this view shown the modifications required when the track circuit energy is alternating current instead of direct current. In Fig. 2 when the 110 coder relay K^D is de-energized, alternating track circuit current is continuously supplied to the primary of transformer A through the back point of contact 27 of this relay, whereas when relay K^D is energized, periodically interrupted alternating current is supplied to the primary of transformer A through the front point of contact 27 and either contact 19 or 20 of the coding device Z^D , depending on whether relay H^D is de-energized or energized. The auxiliary track relay, which is here designated F^A , has a winding 24 which is connected with the rail 1^a through an auto-transformer 26, the primary terminals of which are connected with this rail on opposite 115 sides of the insulated joint 2^a and the secondary terminals of which are connected with relay winding 24. Relay F^A also has a second winding 25 constantly supplied with alternating current from terminals X and Y. 120

The main track relay, which is here designated T^c_A , comprises a winding 22 connected across the track rails, and a second winding 23 supplied with alternating current from the terminals X and Y. As shown in Fig. 1, the 5 track circuit current and the train governing current are of the same frequency. When one frequency is used for track circuit current and a different frequency for train governing current, the windings 23 and 25 of the track 10 relays are preferably controlled in such manner that these windings receive current of the track circuit frequency when track circuit current is being supplied to the track rails, 15 and current of train governing frequency when train governing current is being supplied to the track rails. This feature has nothing to do with my present invention, however, and consequently, it is not illustrated in the accompanying drawing. One 20 means for accomplishing this control of the track relay windings 23 and 25 is illustrated in Letters Patent of the United States No. 1,632,162, granted to C. R. Beall on June 14, 25 1927, for Railway traffic controlling apparatus.

Although I have herein shown and described only two forms of apparatus embodying my invention, it is understood that various 30 changes and modifications may be made therein within the scope of the appended claims without departing from the spirit and scope of my invention.

Having thus described my invention, what 35 I claim is:

1. In combination, a section of railway track, a source of track circuit current at the exit end of said section and a main track relay connected across the track rails at the 40 entrance end of said section, an insulated joint in one track rail at an intermediate point in said section, an auxiliary track relay connected with said one rail on opposite sides of said joint, a signal for said section 45 controlled in part by said two track relays, and means controlled jointly by said signal and said two track relays for supplying train governing current to the rails of said section.

2. In combination, a section of railway 50 track, a source of track circuit current at the exit end of said section and a main track relay connected across the track rails at the entrance end of said section, an insulated joint in one track rail at an intermediate 55 point in said section, an auxiliary track relay connected with said one rail on opposite sides of said joint, a signal for said section controlled in part by said two track relays, a contact operated by said signal and closed 60 when the signal indicates proceed but not when it indicates stop, a coder relay, a pick-up circuit for said coder relay including a back contact of said main track relay and said signal operated contact, a branch around 65 said signal operated contact in said pick-up

circuit including a back contact of said auxiliary track relay, a stick circuit for said coder relay including a front contact of the coder relay and a back contact of said main track relay, and means for supplying train 70 governing current to the rails of said section when said coder relay is energized.

3. In combination, a section of railway track, a source of track circuit current at the exit end of said section and a main track relay connected across the track rails at the entrance end of said section, an insulated joint in one track rail at an intermediate point in said section, an auxiliary track relay connected with said one rail on opposite sides of 75 said joint, a signal for said section controlled in part by said two track relays, and means controlled by said relays and said signal for supplying train governing current to the rails of said section as soon as a train enters the 80 section if said signal indicates proceed but for delaying the supply of such current until the train reaches said insulated joint if the signal indicates stop.

4. In combination, a section of railway 85 track, a source of track circuit current at the exit end of said section and a main track relay connected across the track rails at the entrance end of said section, an insulated joint in one track rail at an intermediate 90 point in said section, an auxiliary track relay connected with said one rail on opposite sides of said joint, a signal for said section, a circuit for said signal controlled by said two track relays and by a manually operable lever in an interlocking tower, and means controlled by said relays and said signal for supplying train governing current to the rails of said section as soon as a train enters the section if said signal indicates proceed, but for delaying the supply of such 95 current until the train reaches said insulated joint if the signal indicates stop.

5. In combination, a section of railway 100 track, a source of track circuit current at the exit end of said section and a main track relay connected across the track rails at the entrance end of said section, an insulated joint in one track rail at an intermediate 105 point in said section, an auxiliary track relay connected with said one rail on opposite sides of said joint, a signal for said section controlled jointly by said two track relays, and means controlled jointly by said signal and said track relays for supplying periodically interrupted alternating train governing current to rails of said section.

6. In combination, a section of railway 110 track, a source of track circuit current at the exit end of said section and a main track relay connected across the track rails at the entrance end of said section, an insulated joint in one track rail at an intermediate 115 point in said section, an auxiliary track relay connected with said one rail on opposite sides of said joint, a signal for said section controlled jointly by said two track relays, and means controlled jointly by said signal and said track relays for supplying periodically interrupted alternating train governing current to rails of said section.

sides of said joint, a signal for said section controlled by said track relays, and means controlled jointly by said signal and said relays for supplying the rails of said section 5 with alternating train governing current periodically interrupted at one frequency or another according to traffic conditions in advance of said section.

7. In combination, a section of railway 10 track, an alternating current track circuit for said section including a track relay connected across the rails at the entrance end of the section, an insulated joint in one track rail at an intermediate point in said section, an 15 autotransformer having its primary terminals connected with said one rail on the opposite sides of said joint, an auxiliary alternating current track relay having a winding connected with the secondary terminal of 20 said transformer, and means controlled jointly by said main and auxiliary track relays for supplying periodically interrupted alternating train governing current to the rails of said section.
- 23 In testimony whereof I affix my signature.
HOWARD A. THOMPSON.
